ADJUSTABLE CAM TIME SEQUENCE CONTROL
 Harold T. Simmons, Indianapolis, Ind., assignor to P. R. Mallory & Co., Inc., Indianapolis, Ind., a corporation of Delaware

Filed Sept. 9, 1963, Ser. No. 307,635

7 Claims. (Cl. 200—38)

This invention relates generally to cam operated timing devices useful in carrying out predetermined functions and/or operations in accordance with a selective program and more particularly to a device capable of being adjusted to a variation of time sequences.

While most similar switch actuating devices are designed for use in automatic washing machines, dishwashers, clothes dryers, etc., the present invention lends itself to many other applications where an electrically timed sequence is required, for example, in vending machines of the liquid dispensing type.

Other types of adjustable switches require a certain amount of guesswork in setting the cams in desired relationship to each other and these usually require some sort of tool to facilitate setting.

It is an object of the present invention therefore, to provide a device having a means for very close incremental cam settings such as 1° variations.

It is another object of this invention to provide a device wherein the cams can be set in varying relationship to each other without the use of tools. It is another object of this invention to provide a versatile switch actuating means whereby the cams can be set quickly and accurately.

It is still another object of this invention to provide a switch actuating means having a plurality of toothed cam sets whereby the center cam which is rigidly fixed to the rotatable shaft, can be used to carry out a repetitive cycle while the outside or moveable cams can be adjusted to provide variable cycles.

In practice, adjustment of the cams is made by axially disengaging the teeth of the end cams from the mating teeth on the faces of the center driving cam and rotating the adjustable cams to the required setting. The cam teeth are biased back into engagement by springs located on each side of a cam set. It is contemplated that the switch actuating means will be driven by an electric motor. Accordingly, the invention resides in the features of construction and arrangement of parts. However, since various embodiments of the invention are conceivable without departing from the spirit thereof it is intended that the description and drawings be considered as illustrative only and not limiting in scope.

In the drawings:

FIG. 1 shows an exploded perspective view of one embodiment of my invention including a typical electric motor driving mechanism as well as the outline of a single snap-action switch, the actuation of which is representative of a use for my invention.

FIG. 2 is a cam and shaft assembly showing a plurality of cam sets biased in their operating positions by a plurality of springs and one cam set separated axially on the shaft in position for making a cycle adjustment.

FIG. 3 is a cross-section view of a typical snap switch showing the rivetless construction comprising two integral eyelet-like bosses. While I have emphasized the novelty and description of the adjustable cams, it will be understood that a complete assembly may contain a combination of conventional cams as presently known and adjustable cams as per the instant invention.

Generally speaking, the construction of the present time sequence control comprising individually adjustable cam sets, fixed sequence cams and unitary switches fulfills a need not heretofore met by existing or prior art. The

2

individual switching stations of the present invention are so constructed that adjustments are now possible by hand manipulation, eliminating the need for various tools as well as parts such as set screws, nuts, washers, etc. These features in the present control are further enhanced by obviating the need for an interval stepping mechanism thereby reducing the cost considerably by the use of a constant speed driving mechanism. Also by staggering the positions of the individual switches it is possible to accommodate more switching stations by utilizing both sides of the control assembly. While the embodiment shown in the drawings also represents a single gang version of my invention, it will be apparent to those skilled in the art that by extending the housing components and utilizing a means of connection such as gears or belts, a multiple gang embodiment can be constructed according to the principles of the invention.

The timing device includes suitable driving means; for example, a clock motor 10 which is not shown in detail since the construction thereof is irrelevant. The clock motor 10 is fastened to an end plate 12 through which the shaft coupling sleeve 11 protrudes to cooperate with cam shaft assembly 14a and floating shaft extension 33 which are connected through a spring clutch 13 to cam shaft assembly 14a. The cam shaft 14 carries a plurality of cam sets, each consisting of a driving cam 15 fixed in position both radially and axially to cam shaft 14, a pair of driven cams 16 and 17 aligned axially on hub 18 of driving cam 15 and held in rotating engagement therewith by springs 19. The driving cam 15 contains a full circle of gear-like teeth 20 on both faces which cooperate with corresponding gear-like teeth 21 on driven cams 16 and 17. Switch mounting plates 22 consist of channel-like strips each having a plurality of perforated switch mounting apertures. Individual switches 23 are mounted at each station by means of eyelet-like bosses 24 formed integral to the switch housing section 25. The bosses are inserted through the perforated channel strip and may be heat staked on the opposite side. The switch itself is held together by similar eyelet-like bosses 26 on switch housing section 25 and may be heat staked as shown in FIG. 3. The unit is considered complete with the assembly of a plate 27 which is similar to plate 12 both of which are mounted to switch mounting channels 22 by screws 28 assembled into threaded apertures 29. Both plates 12 and 27 contain two or more elongated arcuate slots 30 to facilitate radial adjustment of switch mounting channels 22. Reverse manipulation of the shaft 14 is prevented by the use of clutch springs 13 and 32. From the foregoing description of the present invention in conjunction with the accompanying drawings, it will be evident that the invention provides an improved time sequence control featuring ruggedness, simplicity and low cost without sacrificing quality and efficient operation.

I claim:

1. In combination, a timing mechanism for sequentially actuating a plurality of switching devices comprising: a motor, said motor activating a shaft through a pair of spring clutches, said clutches permitting rotation of said shaft in one direction only, said shaft having placed thereon a plurality of adjustable cam sets having predetermined functional contours, said cam sets including a driven cam fixedly connected to said shaft and a plurality of cams having a floating characteristic on said shaft, each of said cams in said cam sets having gear-like teeth on the faces thereof, spring means urging engagement of said gear-like teeth of each of said cams of said cam sets, said gear-like teeth being adapted to provide fine incremental setting of said functional contours at predetermined angles as said cams having a floating characteristic on said shaft are manually displaced with respect to said fixed cam of said cam sets, and a plurality of snap action

switches individually riding on said functional contours of said cams whereby on rotation of said cams by said motor, said contours of said cams actuate adjacent snap action switches, said snap action switches mounted on a frame for said combination by means integral to said snap action switches.

2. In combination, a timing mechanism for sequentially actuating a plurality of switching devices comprising: a motor, said motor activating a shaft through a pair of spring clutches, said clutches permitting rotation of said shaft in one direction only, said shaft having placed thereon a plurality of adjustable cam sets having predetermined functional contours, said cam sets including a driven cam fixedly connected to said shaft and a plurality of cams having a floating characteristic on said shaft, said drive cam centrally located within said cam set, each of said cams in said cam sets having gear-like teeth on the faces thereof, spring means urging engagement of said gear-like teeth of each of said cams of said cam sets, said gear-like teeth being adapted to provide fine incremental setting of said functional contours at predetermined angles as said cams having a floating characteristic on said shaft are manually displaced with respect to said fixed cam of said cam sets, and a plurality of snap action switches individually riding on said functional contours of said cams whereby on rotation of said cams by said motor, said contours of said cams actuate adjacent snap action switches, said snap action switches mounted on a frame for said combination by means integral to said snap action switches.

3. In combination, a timing mechanism for sequentially actuating a plurality of switching devices comprising: a motor, said motor activating a shaft through a pair of spring clutches, said clutches permitting rotation of said shaft in one direction only, said shaft having placed thereon a plurality of adjustable cam sets having predetermined functional contours, said cam sets including a driven cam fixedly connected to said shaft and two cams having a floating characteristic on said shaft, said fixed cam positioned between said two cams having a floating characteristic, each of said cams in said cam sets having gear-like teeth on the faces thereof, spring means urging engagement of said gear-like teeth of each of said cams of said cam sets, said gear-like teeth being adapted to provide fine incremental setting of said functional contours at predetermined angles as said cams having a floating characteristic on said shaft are manually displaced with respect to said fixed cam of said cam sets, and a plurality of snap action switches individually riding on said functional contours of said cams whereby on rotation of said cams by said motor, said contours of said cams actuate adjacent snap action switches, said snap action switches mounted on a frame for said combination by means integral to said snap action switches.

4. In combination, a timing mechanism for sequentially actuating a plurality of switching devices comprising: a motor, said motor activating a shaft, said shaft having placed thereon a plurality of adjustable cam sets having predetermined functional contours, said cam sets including a driven cam fixedly connected to said shaft and a plurality of cams having a floating characteristic on said shaft, each of said cams in said cam sets having gear-like teeth on the faces thereof, spring means urging engagement of said gear-like teeth of each of said cams of said cam sets, said gear-like teeth being adapted to provide incremental setting of said functional contours at predetermined angles as said cams having a floating characteristic on said shaft are displaced with respect to said fixed cam of said cam sets, and a plurality of switches individually riding on said functional contours of said cams, contours of said cams for actuating said switches.

5. In combination, a timing mechanism for sequentially actuating a plurality of switching devices comprising: a motor, said motor activating a shaft through a pair of

spring clutches, said clutches permitting rotation of said shaft in one direction only, said shaft having placed thereon a plurality of adjustable cam sets having predetermined functional contours, said cam sets including a driven cam fixedly connected to said shaft and a plurality of cams having a floating characteristic on said shaft, each of said cams in said cam sets having means for interconnecting said cams of said cam set with other cams of said cam set, on the faces thereof, spring means urging engagement of said means for interconnecting said cams of said cam sets, said means for interconnecting said cams adapted to provide fine incremental setting of said functional contours at predetermined angles as said cams having a floating characteristic on said shaft are manually displaced with respect to said fixed cam or said cam sets, and a plurality of snap action switches individually riding on said functional contours of said cams whereby on rotation of said cams by said motor, said contours of said cams actuate adjacent snap action switches, said snap action switches mounted on a frame for said combination by means integral to said snap action switches.

6. In combination, a timing mechanism for sequentially actuating a plurality of switching devices comprising: a motor, said motor activating a shaft, said shaft having placed thereon a plurality of adjustable cam sets having predetermined functional contours, said cam sets including a driven cam fixedly connected to said shaft and a plurality of cams having a floating characteristic on said shaft, each of said cams in said cam sets having means for interconnecting said cams of said cam set with other cams of said cam set on the faces thereof, means urging engagement of said means for interconnecting said cams of said cam sets, said means for interconnecting said cams adapted to provide incremental setting of said functional contours at predetermined angles as said cams having a floating characteristic on said shaft are displaced with respect to said fixed cam of said cam sets, and a plurality of switches individually riding on said functional contours of said cams, said contours of said cams for actuating said switches.

45 7. In combination, a timing mechanism for sequentially actuating a plurality of switching devices comprising: a motor, said motor activating a shaft, said shaft having placed thereon a plurality of adjustable cam sets having predetermined functional contours, said cam sets including a driven cam fixedly connected to said shaft and two cams having a floating characteristic on said shaft, said fixed cam positioned between said two cams having a floating characteristic, each of said cams in said cam sets having means for interconnecting said cams of said cam set with other cams of said cam set, spring means urging engagement of said means for interconnecting said cams of said cam sets, said means for interconnecting said cams adapted to provide incremental setting of said functional contours at predetermined angles as said cams having a floating characteristic on said shaft are displaced with respect to said fixed cam of said cam sets, and a plurality of switches individually riding on said functional contours of said cams, said contours of said cams for actuating said switches.
